UNITED STATES PATENT OFFICE.

IVAR ERICKSEN, OF CHICAGO, ILLINOIS.

DUPLEX TOOL HOLDER.

Application filed April 30, 1921. Serial No. 465,890.

To all whom it may concern:

Be it known that I, IVAR ERICKSEN, a citizen of the United States, and a resident of Chicago, in the county of Cook and State 5 of Illinois, have invented a new and useful Improvement in Duplex Tool Holders, of which the following is a full, clear, and exact description.

My invention relates to improvements in 10 duplex tool holders, and it consists in the combinations, constructions and arrangements herein described and claimed.

An object of my invention is to provide a device adapted for attachment to the reciprocating ram of a shaper or planer and provided with means for operatively engaging work during both movements of the reciprocating ram.

A further object of my invention is to provide a device of the character described in 20 which a block or head for carrying a cutting tool is arranged to swing freely in one direction, and is held against movement in the opposite direction.

25 A further object of my invention is to provide a device of the character described that is adapted to hold cutting tools of various kinds, whereby a "roughing" cut and a "finishing" cut may be made alternately during the reciprocations of the member propelling the device.

30 A further object of my invention is to provide a device of the character described that is simple in construction and operation, comprises relatively few parts, and is not likely to get out of order easily.

35 Other objects and advantages will appear in the following specification, and the novel features of the invention will be particularly 40 pointed out in the appended claims.

My invention is illustrated in the accompanying drawings, forming part of this application, in which

Figure 1 is a side elevation, showing the 45 device operatively applied.

Figure 2 is a bottom plan view of the device,

Figure 3 is an end view of a portion of the device,

50 Figure 4 is a bottom plan view of the portion of the device shown in Figure 3,

Figure 5 is a side elevation of a block or carrier embodied in the device for supporting a cutting tool, and

55 Figure 6 is a bottom view of the tool carrying block.

In carrying out my invention, I provide a body portion 1 having a shank 1' that is adapted for connection with a reciprocating ram, indicated generally at 2, of a planer or 60 shaper. The body portion 1 is formed with integral lateral wing extensions or abutments 3 and 4 at its lower end. The abutments or wing extensions 3 and 4 are positioned diagonally with respect to one another and are substantially identical with each other in conformation. It is to be noted that the inner side wall of each of the wing extensions is beveled inwardly from the outer face thereof as indicated at 5 and 65 6 respectively (see Figures 1 and 2) and that each inner side wall is inclined so that each abutment terminates short of the upper end of the body portion 1. Each of the inner side walls of the abutments 3 and 4 70 cooperates with the adjacent side wall of the body portion 1 to provide a recess indicated at 7 and 8, such recesses being 75 diagonally disposed with respect to each other.

The body portion 1 has integral trunnions 80 9 and 10 extending within the recesses 7 and 8 respectively so that the ends thereof are substantially flush with the outer faces of the abutments 3 and 4 respectively. The trunnion 9 is formed with a threaded axial bore 11 and a block or head 12 having an opening 13 extending transversely therethrough is maintained in the position illustrated in Figures 1 and 2 when a cap screw 14 is threaded into the axial bore 11. The 90 block or head 12 is substantially rectangular in form, as clearly shown in Figures 5 and 6 and is cut away at 15 at its upper end and at 16 at its lower end so that the weight thereof will tend to maintain it in vertical 95 position. Consequently, the end wall 17 thereof which is beveled to conform with the adjacent wall of the abutment 3 will normally be maintained by gravity against the adjacent wall of the abutment 3. The block 100 or head 12 is fashioned with a non-circular opening 18 therethrough adapted to receive the shank of a cutting tool 19. A set screw 20 threaded into a transverse opening 21 communicating with the passage 18 provides 105 a means for maintaining the cutting tool 19 in adjusted position in the passage 18, which is in effect a socket.

A second block or head 22 is disposed in the recess 8. The block or head 22 is precisely identical with the block 12 and is formed with a transverse opening 23 there-

through adapted to receive the trunnion 10. A cap screw 24 threaded into an axial bore 25 in the end of the trunnion 10 prevents displacement of the block 22 from the recess 5 8. The block or head 22 has an opening 26 therethrough adapted to receive a cutting tool 27 that is maintained therein by means of a set screw 28 threaded into an opening (not shown) that corresponds to the opening 10 21. Further description of the block or head 22 is deemed unnecessary since the same is precisely identical with the block or head 12.

From the foregoing description of the various parts of the device, the operation thereof may be readily understood. The ram 2 reciprocates horizontally so that the cutting tools 19 and 22 are moved across the surface of work that is indicated at 29. When 20 the ram 2 is moving toward the left hand side of the sheet, the cutting tool 19 will operatively engage the work 29 so that a desired cut will be made. At this time, the contact of the work 29 with the cutting tool 27, which is not disposed for operative engagement when the ram is moving in that direction, may cause the block or head to swing about the trunnion 10 against the action of gravity. When the movement of the 25 ram is reversed, the cutting tool 27 will operatively engage the work while the cutting tool 19 may swing freely in the direction opposite to the movement of the ram. It will thus be observed that I provide a device 30 having means for accomplishing desired cuts in a work during the movement of the reciprocating ram of a shaper or a planer in each direction, and consequently a great saving results in that a maximum of work may be 35 accomplished by a given machine in a minimum time and without any increased expenditure of power. The cutting tools 19 and 27 may be precisely identical with one another or may be adapted for different uses, 40 as for instance, the tool 19 may be a "roughing" tool, while the tool 27 may be a "finishing" tool and both the finishing and roughing operations may be effected during a complete reciprocation of the actuating ram. 45 One of the cutting tools may be positioned to extend below the other cutting tool so that a deeper cut will be made thereby. The 50 passages or sockets 18 and 23 are preferably non-circular so that rotation of the shanks 55 of the cutting tools 19 and 20 is precluded. The device is relatively simple in construction and each cutting tool is positively held for operative engagement with the work during a movement of a moving part of the 60 machine to which the device is applied in

one direction, and is permitted to swing freely when the moving part is moved in the opposite direction.

I claim:

1. In a device of the character described, 65 a body portion having a shank arranged for connection with a reciprocating ram of a surfacing machine, said body portion being formed with integral extensions to opposite sides thereof and with oppositely extending 70 trunnions, and a block mounted on each trunnion to swing freely in one direction from normal position against the corresponding extension, each block being provided with a socket adapted to receive a cutting tool. 75

2. In a device of the character described, 80 a body portion having a shank arranged for connection with a reciprocating ram of a surfacing machine, said body portion being formed with integral extensions to opposite 85 sides thereof and with oppositely extending trunnions, and a block mounted on each trunnion to swing freely in one direction from normal position against the corresponding extension, each block being provided with a socket adapted to receive a cutting tool, said integral extensions being relatively positioned so that the tool holding blocks may swing freely in opposite directions. 90

3. A device of the type described comprising 95 a body having a vertical plate-shaped portion, laterally aligned trunnions carried by the upper end of said plate, and cutter 100 holders pivotally carried by said trunnions, and being adapted to swing into a vertical position by gravity, and stops carried by said plate and being adapted to prevent the movement of said holders in one direction, and to permit the movement of the 105 holders in the other direction, whereby said 110 holders are free to swing in opposite directions with respect to each other.

4. A device of the type described comprising 115 a body having a vertical plate-shaped portion, laterally aligned trunnions carried by the upper end of said plate, and cutter 120 holders pivotally carried by said trunnions and being adapted to swing into a vertical position by gravity, stops carried by said 125 plate and being adapted to prevent the movement of said holders in one direction, and to permit the movement of the holders in the other direction, whereby said 130 holders are free to swing in opposite directions with respect to each other, said holders having 135 square sockets therein adapted to receive cutters, and cutters adjustably carried by said sockets.

IVAR ERICKSEN.
